UNITED STATES PATENT OFFICE

98,874

DESIGN FOR AN APPLICATOR

Rosemarie Lewis, Los Angeles, Calif.

Application July 2, 1935, Serial No. 57,490

Term of patent 14 years

To all whom it may concern:

Be it known that I, Rosemarie Lewis, a citizen of the United States, residing at Los Angeles, in the county of Los Angeles and State of California, have invented a new, original, and ornamental Design for Applicators, of which the following is a specification, reference being had to the accompanying drawing, forming part thereof.

Fig. 1 is a perspective view of the applicator with the plunger partly retracted,

Fig. 2 is a side elevational view of the applicator shown in Fig. 1, in closed position, and

Figs. 3 and 4 are end elevations looking from front and rear, respectively.

I claim:

The ornamental design for an applicator, as shown.

ROSEMARIE LEWIS.
